UNITED STATES PATENT OFFICE.

LESTER PATEE, OF PEORIA, ILLINOIS, ASSIGNOR TO ABRAM H. RYAN, OF SAME PLACE.

IMPROVEMENT IN SOLDERING-IRONS.

Specification forming part of Letters Patent No. **29,039**, dated July 3, 1860.

To all whom it may concern:

Be it known that I, LESTER PATEE, of the city and county of Peoria, and State of Illinois, have invented a new and useful Improvement in Soldering-Irons; and I do hereby declare the following to be a full and exact description of the same, reference being had to the accompanying drawings, and to the letters of reference marked thereon, in which—

Figure 1 is a perspective view. Fig. 2 represents the outer covering or "shoe" B, with ring H connected to the shoe B by spiral springs G and wire J J. Figure 3 shows "heater" A and handle C, with its groove E and recess P, made to receive the wire J and ring H, as shown in Fig. 1. Fig. 3 also shows the iron rod S that connects the heater A to the handle C.

The nature of my invention consists in the employment of a cast or wrought iron heater, A, (see Fig. 3,) provided with a covering or shoe, B, (see Fig. 2,) made of sheet-copper, and securing the same to the heater A by a spring, (marked G,) and wires J J, or any other arrangement that will keep a constant tension on the shoe B and exert a force sufficient to keep the shoe from becoming loose on the heater A while the heater is cooling and contracting and the shoe is heating and expanding. I make a groove in the handle C (see Fig. 3) to receive the wire J and prevent its being in the way of the hand when the iron is in use. At the end of the wooden handle C, I make a recess, P, (see Fig. 3,) to receive the ring H and hold it in position while the soldering-iron is being used.

In order to heat my soldering-iron, I detach the shoe B from the heater A by withdrawing the ring H from the recess P. The heater being tapering, may then be readily withdrawn from the shoe. I usually make the heaters of cast iron, casting the iron around the iron rod S, as this secures the rod S to the heater in the cheapest and most permanent way, and it also has the advantage of more uniformity in the size and shape of the heaters. When the heater is hot and ready

for use, it may readily be attached to the shoe by inserting the point of the heater into the shoe and pulling the ring H, so as to stretch out the spiral spring long enough to allow the ring H to enter the recess P. This secures the shoe to the heater, and the force exerted on the shoe by the spiral spring effectually prevents the shoe from becoming loose as the heater contracts by cooling. I usually employ two or more heaters at a time, all being made to fit the same shoe, while one shoe only will be required for each person to work with.

I substitute a very cheap metal (cast or wrought iron) for copper, and thereby reduce the expense of making soldering-irons five hundred per cent., and the almost indestructible nature of the material of which the heater is composed renders it capable of being heated by stone-coal without injury, thus rendering it useful in every family for repairing tinware, &c.

I do away with all liability of destroying the part of the iron that is tinned, as I do not expose the copper shoe to the heat of the fire.

The work and delay of cleaning the soot and ashes from the point of the soldering-iron every time it is taken from the fire is entirely avoided, and this iron can be used at a much higher temperature than can be applied to the ordinary soldering-iron without danger of destroying the "face" or tinned part of the iron. Consequently smoother soldering can be done with it, and much more work can be done at one heating of the iron.

What I claim as new, and desire to secure by Letters Patent, is—

The use of a heating center of wrought or cast iron for soldering in connection with a movable tinned copper cap when the latter is constructed with a spiral spring; as set forth, for the purpose of keeping the cap and center in contact under varying temperatures.

LESTER PATEE.
